TRICOLOR TELEVISION PICTURE TUBE

Theodore Miller, Los Angeles, Calif., assignor to Westinghouse Electric Corporation, East Pittsburgh, Pa., a corporation of Pennsylvania

Application February 1, 1952, Serial No. 269,457

9 Claims. (Cl. 178—5.4)

My invention relates to cathode ray tubes, and more particularly to a tube for reproducing color television pictures.

In my copending application, Serial No. 243,487, filed August 24, 1951, there is disclosed a method of quenching the luminescence of phosphor materials by subjecting the phosphors to a high frequency electric field.

In accordance with the prior art of which I am aware, a large number of ideas have been expressed for systems for the production of color television pictures. While many of these have some advantages, nevertheless, it is believed that most of the proposed systems have certain undesirable characteristics which can not be readily overcome.

It is accordingly an object of my invention to provide an improved cathode ray tube.

Another object of my invention is to provide an improved color television tube.

Still another object of my invention is to provide a color television tube which controls the colors produced by employing the principle of quenching phosphors with high frequency electric fields.

The novel features which I consider characteristic of my invention are set forth with more particularity in the appended claims. The invention, however, with respect to both the organization and the operation thereof, together with other objects and advantages may be best understood from the following description of specific embodiments when read in connection with the accompanying drawing, in which:

The sole figure is a schematic showing of an apparatus embodying my invention.

In accordance with my invention, I provide an envelope 2 of glass which is substantially larger in diameter at one end than it is at the other end. In the small end of the envelope there is provided an electron gun 4 for producing a beam of electrons, in a manner well known in the art. In the large end of the glass envelope 2 there is provided a screen 6 oriented so that electrons from the electron gun 4 will impinge upon the screen 6. Deflection coils 8 are provided about the envelope 2 near its center for deflecting the electron beam so as to produce scanning of the screen 6. Between the deflection coils 8 and the screen 6 an anode electrode 10 is provided for accelerating electrons discharged by the gun 4. The screen 6 comprises a layer of transparent conducting material 12 which may be of relatively large thickness so as to support the other elements of the screen. A plurality of red, green and blue phosphor strips 14, 16, 18 are placed on the transparent conducting layer 12 between that layer and the electron gun 4. The few such strips shown in the drawing are, of course, merely indicative of the orientation of the much larger number of strips which would actually be employed in practice. The phosphor strips 14, 16, 18 are arranged in rotation so that any color strip; e. g., one of the red strips 14, lies between two strips of different colors; e. g., a green strip 18 on

2

one side and a blue strip 16 on the other. The phosphor strips 14, 16, 18 are preferably separated by small distances from each other. Opposite each of the phosphor strips 14, 16, 18 and extending parallel thereto there is a strip of electrical conductors 20, 22, 24 such as a very thin coating of aluminum. The aluminum strips 20, 22, 24 adjacent the phosphor strips 14, 16, 18, lie between the phosphor strips and the electron gun 4. It is, therefore, desirable that the aluminum strips 20, 22, 24 be very thin.

Connections are supplied for providing a first set of electrical oscillations to the aluminum strips 20 adjacent the red phosphor strips, a second set of electrical oscillations to the aluminum strips 22 adjacent the blue phosphor strips 16 and a third set of electrical oscillations to the aluminum strips 24 adjacent the green phosphor strips 18. The aforesaid oscillations are preferably in the radio frequency range. For example, in the order of 10 megacycles. The electrical oscillations to be applied to the aluminum strips 20, 22, 24 are supplied by a radio frequency oscillator 26 to the grid of three vacuum tubes. The first vacuum tube 28 has its plate 30 connected to the aluminum strips 20 adjacent the red phosphors 14, the second vacuum tube 32 has its plate 34 connected to the aluminum strips 22 adjacent the blue phosphors 16, and the third vacuum tube 36 has its anode 38 connected to the aluminum strips 24 back of the green phosphor strips 18. A bias control potential is applied in synchronism with the received color signals to the grids of the three vacuum tubes. These bias control potentials are applied so that when the information being reproduced by the electron gun 4 relates to the red picture, the first vacuum tube 28 is non-conducting and the second and third vacuum tubes 32, 36 are conducting. Thus, when the screen 6 is being scanned with a beam of electrons having red information impressed thereon, a high frequency field is applied to the aluminum strips 22, 24 which lie adjacent the blue and green phosphor strips. These high frequency oscillations when applied to the aluminum strips 20, 22, 24 produce a field between the aluminum strips and the transparent conducting layer 12 on the opposite side of the phosphor strips 14, 16, 18. Therefore, when the high frequency electrical oscillations are applied to the aluminum strip 22 adjacent the blue phosphor strip 16, a high frequency field is produced across the blue phosphor strip 16 which quenches the ability of the phosphor strip 16 to luminesce.

In the operation of the apparatus shown in the drawing, the electron beam has impressed thereon, red information. At this time, radio frequency fields are being applied across the blue and green phosphors 16, 18. Therefore, electrons produced by the electron gun 4 and impinging on the blue and green phosphors 16, 18, will have substantially no effect because of the quenching effect of the radio frequency fields. On the other hand, no radio frequency fields are applied across the red phosphor 14. Therefore, when the electrons strike the red phosphor strips 14, red light will be emitted by those phosphor strips, in response to the electrons impinging thereon. Thus, when the electron beam is scanning the screen 6 with red information, only red light can be emitted by the screen.

Although I have shown and described specific embodiments of my invention, I am aware that other modifications thereof are possible. My invention, therefore, is not to be restricted except insofar as is necessitated by the prior art and the spirit of the invention.

I claim as my invention:

1. In combination, a television tube comprising an envelope of dielectric material, means for producing a beam of electrons near one end of said envelope inside said

envelope, a layer of transparent conducting material near the other end of said envelope inside said envelope, a plurality of fine strips of phosphor material capable of emitting light of a first frequency located near said transparent conducting material and extending parallel to the surface thereof, a plurality of phosphor strips capable of producing light of a second frequency, said second phosphor strips being interposed between said first phosphor strips, a strip of conducting material near each of said phosphor strips on the opposite side of said phosphor strips from said transparent conducting material, means for applying a first potential to said transparent conducting coating, and means for supplying a first radio frequency potential to the conducting strips in back of said phosphor of a first material, and means for supplying a second radio frequency potential to said conducting strips located in back of said second phosphor strips.

2. Apparatus substantially as described in claim 1, characterized in that means are provided for varying the radio frequency power applied to said conducting strips in accordance with a signal.

3. A television tube comprising a plurality of first phosphor strips capable of emitting light of a first frequency, a plurality of second phosphor strips interspersed among said first strips capable of emitting light of the second frequency, means for impressing a first radio frequency field across said first phosphor strips, means for impressing a second radio frequency field across said second phosphor strips independently of the potential applied across said first phosphor strips, and means for causing high velocity electrons to impinge on said phosphor strips.

4. Apparatus substantially as described in claim 3 characterized in that said means for impressing a first field and said means for impressing a second field are variable in accordance with a signal.

5. A color television tube comprising a plurality of phosphor strips, some of said phosphor strips being capable of producing light of a first color and other of said phosphor strips being capable of producing light of a second color, means for applying a radio frequency field across said phosphor strips of a first color during a first time interval and means for applying a radio frequency field across said phosphor strips of a second color during a second time interval.

6. A color television tube comprising means for producing an electron beam, an image screen, said image screen comprising a transparent conductive layer of material, a phosphor layer comprising a plurality of individual strips deposited on said conductive layer and each of said phosphor strips having an individual electron permeable conductive coating thereon, said transparent conductive layer and said individual coatings being adapted for apply-

ing a radio-frequency field thereto to control the luminescence of said phosphor strips associated with said selected individual conductive layers.

5 7. A color television tube comprising an image screen, said image screen having a plurality of groups of phosphor coated elemental areas on a conductive surface, said elemental areas comprising a phosphor material capable of emitting light of a color individual to that area and insulated electrically transparent conductive coatings on each of said elemental phosphor areas, said conductive surface and said insulated conductive coating being adapted for supplying a radio-frequency field thereto to quench the luminescence of said elemental areas of phosphor material associated with said selected conductive coatings.

10 15 8. A color television tube comprising an image screen having a plurality of groups of elemental areas of phosphor material, each elemental area of phosphor material within a group being limited in its light representation to one selected component color, means for scanning a luminescent image on said screen, and means for decreasing the luminescence of selected elemental areas of phosphor by impressing a radio frequency field across those selected elemental areas of phosphor.

20 25 9. A color television tube comprising an image screen having a plurality of groups of substantially parallel phosphor strips deposited upon a conductive surface, each strip of said groups being limited in its light representation to one selected component color, individual insulated conductive coatings deposited on the exposed surface of said parallel strips of phosphor material, means connecting together all those individual conductive coatings on said phosphor strips of similar color light representation, an electronic scanning means for developing an image on said screen by a scanning operation, and means for modulating said scanning means with signal representative of one color while simultaneously impressing a radio-frequency field across said phosphor strips other than said phosphor strips representative of the color signal impressed on said scanning means to quench the luminescence therefrom.
